(57) **CLAIM**

I claim the ornamental design for a watch stand, as shown and described.

DESCRIPTION

FIG. 1 is a top, side perspective view or a watch stand.

FIG. 2 is a top, rear perspective view thereof.

FIG. 3 is a left-side elevation view thereof.

FIG. 4 is a right-side view thereof.

FIG. 5 is a front elevation view thereof.

FIG. 6 is a rear elevation view thereof.

FIG. 7 is top plan view thereof; and,

FIG. 8 is a bottom plan view thereof.

The broken lines in the drawings illustrate optional accessories of the watch stand that form no part of the claimed watch stand design.
